UNITED STATES PATENT OFFICE.

DANIEL BENNETT, OF BALDWIN TOWNSHIP, ALLEGHENY COUNTY, PA.

DESIGN FOR GLASSWARE.

Specification forming part of Design No. 7,550, dated July 14, 1874; application filed July 3, 1874.
[Term of Patent 7 years]

CASE A.

To all whom it may concern:

Be it known that I, DANIEL BENNETT, of Baldwin township, Allegheny county, Pennsylvania, have invented a new and original Design for Glassware, of which the following is a specification:

A set of glassware, having the configuration and ornamentation characteristic of my design, is represented in the accompanying drawing.

The general configuration of the several pieces composing the set is adequately represented by the drawing, and cannot be made clearer by description. Superadded to that configuration is the scalloped edge, which is found in all of the pieces, excepting the goblet No. 7 and the cream-pitcher No. 6, which lat-

ter is scalloped for that portion only of its edge between the spout and handle.

No. 1 is a spoon-glass. 2, 3, and 13 are what are termed "nappys," the former two having covers. 4 is a flanged butter-dish. 5 is a sugar-bowl. 8 is a celery-glass; 9, an oval dish; 10, a covered bowl; 11, a flared saucer; 12, a flared bowl; and 14, a covered saucer.

What I claim is—

The design for glassware, of the configuration and ornamentation set forth.

In testimony whereof I have hereunto signed my name this 22d day of June, A. D. 1874.

DANIEL BENNETT.
